Wells and Greene

ATTORNEY

UNITED STATES PATENT OFFICE.

EDWARD W. SHOESMITH, OF LENA, ILLINOIS, ASSIGNOR OF ONE HALF TO
GEORGE BREON, OF SAME PLACE.

MACHINE FOR WINDING FENCE-WIRE.

SPECIFICATION forming part of Letters Patent No. 324,887, dated August 25, 1885.

Application filed May 29, 1885. (No model.)

To all whom it may concern:

Be it known that I, EDWARD W. SHOESMITH, a resident of Lena, in the county of Stephenson and State of Illinois, have invented certain new and useful Improvements in Fence-Building Machines; and I do hereby declare the following to be a full, clear, and exact description of the invention, such as will enable others skilled in the art to which it pertains to make and use the same.

My invention relates to improvements in machines for taking up or paying out wire in building or taking down wire fencing. It is fully explained in the following specification, and shown in the accompanying drawings, in which—

Figure 1 is a side elevation of a machine embodying my invention; Fig. 2, a plan of same; Fig. 3, a side elevation of the hinged box, in which is journaled one end of the spool-shaft of the machine; Fig. 4, a front elevation of the adjustable wire-guide, which is fastened to the front cross-bar of the bed of the machine; Fig. 5, a side elevation of one of the 25 pawls of the pawl-and-ratchet mechanism which actuates the spool-shaft.

In these views, A A' are the side bars, and O O' O'' the cross-bars, of a preferably rectangular cart-bed, the side bars being terminated at the end opposite the cross-bar O in suitable handles, C C', and a floor or bottom, D, being fastened to the cross-bars O' O'' to form a box for tools, staples, and other articles used in fence construction. Near the front end of the bed suitable dependent brackets L L' are bolted to the lower faces of the side bars, A A', respectively, and in these brackets is journaled an axle, M, on which are mounted two wheels, B, of any desired size and construction. The wheels B support the front of the cart and serve as a means of moving it from place to place, and the rear of the cart is supported by two suitably-braced legs, E, fastened to the side bars and the cross-bar O''.

On the side bar A is bolted a bearing, f, which supports three pinions, H H' H'', the pinions H H' being loosely mounted on glands formed on the bearing, and the pinion H'' being rigidly mounted on a shaft, H''', journaled in the bearing and projecting beyond the inner face thereof. (See Fig. 2.)

In the inner end of the short shaft H''' is a square socket, N', (indicated by dotted lines in Fig. 2,) and in this socket rests the end of a square spool-shaft, N, the opposite end of which is journaled in a box, k l, on the side bar A'. The box k l consists of a stationary lower half, k, and a swinging upper half, l, the two parts being connected at one end by a pivot, j, and at the other end by a bolt and a wing-nut, i. The nut i may be readily detached from its bolt, and the box may then be opened and the shaft N removed from the machine.

On the spool-shaft, near its square end, is rigidly fastened a dog, m', having suitable spurs for entering the end of an ordinary barbed-wire spool, and a similar dog, m, is mounted loosely on the opposite end of said shaft, and provided with a set-screw, i', for setting it in any desired position. By means of the dogs m m' a spool of barbed wire may be fastened rigidly to the shaft N in the position shown in Figs. 1 and 2, and if the end of the wire be fastened to a post and the cart be drawn in the direction indicated by the arrow a in Fig. 1, the spool F and the shaft N will be rotated and the wire unwound from the spool.

In unwinding the wire, to insure an even delivery, a tension is put on the shaft N by means of a spring tension-lever c, pivoted at e, and having a curved end, e', which conforms to the circle of the pinion H''. A pin, g, is set in the side of the side bar, A, in such a position that when the end c of the tension-lever is above it the curved end e' puts no pressure on the pinion H'', but if the end c be sprung downward and placed under the pin g the end e' is pressed strongly against the pinion, and acts as a brake or tension on the rotation of the spool.

The pinion H, already mentioned, engages with the pinion H'', and the pinion H' engages with the pinion H, the pinions H H' being of the same diameter and the pinion H'' being preferably of less diameter, in order to give it increased speed. Two levers, I I', are pivoted at the centers of the pinions H H', respectively, and pawls J J' are pivoted to the levers I I', respectively, and engage the pinions H H' on opposite-sides. The free ends of the levers I

I' are so connected as to move up or down together, the one sliding on the other to compensate for the distance between their centers of oscillation. It is evident that as the free ends 5 of the levers I I' are raised the pawl J' rotates the pinion H', whose motion is transmitted through the pinion H to the pinion H'', and that as the free ends of the levers are pressed downward the pawl J rotates the pinion H and 10 through it the pinion H''. Thus, whether the levers be raised or depressed, the pinion H'' is turned in the direction indicated by the arrow a', Fig. 1, and the wire is thus reeled upon the spool.

15 During the operation of reeling, each of the pawls J J' is held in engagement by a spring, p, Fig. 5, one end of which is fastened to the pawl, while the other end presses against a pin, s, on the bar or lever to which the pawl is pivoted. In unreeling, however, the springs p are released from the pins s, their free ends taking the position p'', Fig. 5, and the pawls are disengaged from the pinions H H', thus allowing all the pinions to turn freely without moving the levers I I'.

20 The wire, both in reeling and unreeling, is carried through an adjustable guide fastened to the front cross-bar, O, of the cart, and consisting of two vertical bars, q q', and two horizontal rods, r r', crossing the bars. The bar q is fastened to the cross-bar O by a bolt, n, and the bar q' is fastened by a bolt, n', which may be passed through any one of a series of holes in the cross-bar. Each of the rods r r' is fastened 25 rigidly to the bar q and passes through a hole in the bar q', so that the bar q' may be adjusted 30 without moving or adjusting the rods.

35 It is evident that nearly all the features of this machine may be used whether the spool-shaft be rotated by a reciprocating lever and pawl-and-ratchet mechanism or by some other means; and I desire, therefore, not to limit my invention to the combination of other novel features with the mechanism shown for turning 40 the spool. It is also plain that a single reciprocating lever, provided with two pawls, which engage either the pinion H or the pinion H'', may be substituted for the levers I I', the pawls J J', and the arrangement of pinions 45 shown.

50 I consider the mechanism shown in the drawings the most satisfactory pawl-and-ratchet device which can be applied to this machine for converting the movement of a reciprocating lever into the rotation of the spool-shaft, but there are evidently other forms 55 which can be substituted for it.

Having now described and explained my invention, what I claim as new, and desire to 60 secure by Letters Patent, is—

65 1. In a machine of the class described, the combination, with a cart-body, of a suitably-mounted spool-shaft, a reciprocating lever pivoted to the cart-body, and pawl-and-ratchet mechanism connecting the lever and the spool-

shaft, whereby the reciprocal motion of the lever rotates the spool-shaft.

2. The combination of the cart-body A A', the pinion H'', and its socketed shaft H''', the spool-shaft N, having one of its ends cylindrical and the other non-cylindrical, and the separable box k l, the cylindrical end of the shaft being journaled in said box and the non-cylindrical end stepped in the socket of the shaft H''', substantially as shown and described, and for the purpose set forth. 75

3. The combination of the shaft N and the dogs m m', mounted on said shaft, one of said dogs being removable at will and both of said dogs being adapted to engage a wire spool and hold the same in position on the shaft N, the separable box k l, in which one end of said shaft N is journaled, and the socketed shaft H''', in which the other end of said shaft N is stepped, and means, substantially 85 as shown and described, for rotating said socketed shaft H''', substantially as and for the purpose set forth.

4. The combination, with the cart-frame A A', of the pinion H'', and its shaft H''', the 90 spool-shaft N, having one of its ends stepped in the shaft H''' and the other journaled in a box on the frame, the pinions H H', levers I I', and pawls J J', substantially as shown and described, and for the purpose set forth.

5. The combination, with the cart-frame A A' O and a spool-shaft mounted and rotating thereon, of the wire-guide attached to the front of the machine and consisting of the vertical bars q q' and the horizontal rods r r', 100 substantially as shown and described, and for the purpose set forth.

6. The combination of the pinion H'' and its short shaft H''', the cart-frame on which they are mounted, the shaft N, rotating with 105 the shaft H''', and the brake c and stop g, adapted to retard the rotation of the pinion H'', substantially as shown and described, and for the purpose set forth.

7. The combination, with the pinions H H' 110 H'', levers I I', and pawls J J', of the springs p and pins s, constructed and combined substantially as shown and described, whereby the pawls may be held in or out of engagement, as desired, and the reverse rotation of the pinions be permitted or prevented at will. 115

8. The combination of the cross-bar O, the bars q q', one of which is stationary and the other laterally adjustable, and the horizontal rods r r', each attached securely at one end to 120 one of the bars q q' and passing through the other of said bars, substantially as shown and described, and for the purpose set forth.

In testimony whereof I have signed this specification in the presence of two subscribing witnesses.

EDWARD W. SHOESMITH.
